SCREW CUTTING DEVICE FOR AUTOMATIC LATHES

Application filed August 2, 1929, Serial No. 382,865, and in Germany May 24, 1928.

The present invention relates to screw cutting devices for single and multi-spindle automatic lathes. Screw cutting devices for single spindle automatic lathes are known in which the automatic forward and backward motion of the tool is effected by a threaded mandrel which screws into and out of a stationary mandrel guide. The known arrangements exhibit the disadvantage that the direction of rotation of the tool spindle and of the threaded mandrel must be reversed periodically so that energy losses are involved in the necessary braking and accelerating operations. Also screw cutting devices on multi-spindle automatic lathes are known in which the tool is pressed against the blank for the purpose of starting the cut whereas the traverse for cutting the thread is effected by the threads of the tool and blank which are in engagement. The disadvantage of this device is that the sides of the thread on the blank have to take up the axial pull. The present invention avoids these disadvantages. It consists in that the threaded mandrel rotates unidirectionally in a rotary mandrel guide and is caused to screw out of and into said guide by being driven alternately at a speed smaller than or greater than the speed of rotation of the mandrel guide. The tool spindle carrying the tool 28 is mounted so as to be rotatably and axially displaceable in the tool slide 29, and is driven from the shaft 23 with which it is connected by the connecting sleeve 25 so as to be readily disengageable. The mandrel 26 is arranged on the shaft 23 between the collar 24 and the connecting sleeve 25 and is prevented from rotating relatively to the latter by means of a tongue and groove. The mandrel screws out of and into the mandrel guide 18 in a manner to be described subsequently and in so doing causes the forward and backward motion of the tool 28. In contradistinction to the known devices the mandrel guide 18 also rotates and the mandrel 26 is screwed into and out of the latter, without alteration of the sense of rotation by being driven alternately at a speed smaller than or greater than the speed of rotation of the mandrel guide 18. The drive of the mandrel 26 and the mandrel guide 18 is effected together with that of the blank 6 in the following manner. The blank carrying spindle 5 carrying the blank 6 is driven from the main shaft 1 by means of the gearing 2, 3, 4. The intermediate shaft 9 is driven from the main shaft 1 by means of the gear wheels 7, 8 and from this intermediate shaft the mandrel guide 18 is driven by means of the gearing 10, 12 and the rotation of the mandrel 26 is derived either from the gearing 8, 14 or by gearing 11, 13. The transmission ratio may, for example, be so chosen that the mandrel guide 18 rotates in the same direction and at the same speed as the blank 6 whereas the mandrel 26 is driven by means of the gearing 11, 13 at a lower speed of rotation than the mandrel guide 18, or on the other hand by the gearing 8, 14 at a higher speed of rotation, so that the mandrel screws out of or into the guide respectively. Thus on the forward traverse the tool 28 has a speed of rotation smaller than that of the blank 6 but in the same direction and consequently cuts a thread in the blank. On the return motion the tool 28 still rotates in the same direction as the blank 6 but with a higher velocity and consequently makes the return motion. In the embodiment described the pitch of the thread of the mandrel 26 is equal to that of the thread to be cut. It can, however, be different by employing a different transmission ratio. If a left handed thread is to be cut instead of a right handed one, then the tool passes on to the blank at the higher speed and is withdrawn from it at the lower speed. The connection between the gear wheel 12 and the mandrel guide 18 is effected by means of a sleeve 15 connected with the gear wheel 12 by a pin 16, the pin 16, Fig. 2, engaging in a slot of the collar 17 on the mandrel guide 18 so that this latter rotates with the gear wheel 12. The mandrel guide 18 is held against axial motion in the sleeve 15 by the

threaded cap 20 whereas the position of the gear wheel 12 and the sleeve 15 connected thereto is determined by threaded ring 19. By unscrewing the threaded cap 20 and releasing the connecting sleeve 25, the left hand end of the shaft 23 can be released by displacing the connecting sleeve 25 to the left so that the mandrel 26 together with the mandrel guide 18 can be withdrawn and ¹⁰ changed.

The alternate coupling of the shaft 23 and of the mandrel 26 connected thereto with the transmission gearing 11, 13 on the one hand and 8, 14 on the other, is effected by means ¹⁵ of the coupling sleeve 22 which is axially displaceable on a hollow shaft 21 in which the shaft 23 in turn is guided by means of a tongue and groove so as to be axially displaceable. In its left and right hand end ²⁰ positions the coupling sleeve 22 engages in the hubs formed as couplings of the gear wheels 13 and 14 respectively so that the shaft 23 and the mandrel 26 are given a smaller speed of rotation than the mandrel ²⁵ guide 18 in the left hand end position of the coupling sleeve 22 and a higher speed in the right hand end position of the sleeve 22 and in consequence screw out of and into the mandrel guide 18, the tool 28 cutting a thread ³⁰ in the blank 6 and being again withdrawn therefrom. In the central position of the sleeve 22 in which it is not connected with the hub of either wheel the shaft 23 will be rotated at the same speed as the mandrel ³⁵ guide 18 in consequence of the friction in the threads so that in this position of the coupling sleeve a forward or backward motion of the tool spindle 27 does not occur.

The screw cutting arrangement is automatically reversed in the following manner: ⁴⁰ The rods 30, 31, 32 engage in the connecting sleeve 25 and transmit the axial motion of the tool spindle 27, which in the case of cutting the thread is towards the left, to a ⁴⁵ release member journalled in guides 34 and provided with a wedge-shaped trip 33. In its forward motion the wedge-shaped oblique surface of the release member 33 engages the spring controlled pawl 35 and raises the same. ⁵⁰ In consequence the swinging lever 36 is released and the coupling sleeve 22, shown in its left hand end position, brought by the action of the spring 37 and the levers 38, 39 to the right hand end position and thus into ⁵⁵ engagement with the gear 14 so that the tool 28 is again withdrawn from the previously cut thread. The length of the thread to be cut can be adjusted by setting the arm 32 and the release member 33 connected there- ⁶⁰ with.

In order to return the coupling sleeve 22 from the right hand end position to the central and to the left hand end position a controlling disc 42 is provided which is driven ⁶⁵ correspondingly slowly from the control

shaft 43 of the machine by means of a mono-toothed coupling 45. This control disc is provided with two preferably adjustable projections 40, 41 of different heights which in turn contact with the lower end of the swinging arm 36 and thus bring the latter and at the same time the coupling sleeve 22 first into the central and then into the left hand end position, the pivoted lever 36 being held in position by means of the two notches on ⁷⁰ the pawl 35. Before the coupling sleeve 22 passes from the middle position to the left hand end position (advance of the tool) the blank 6 must be exchanged for a fresh one, a certain time being required for this operation. During this period the control discs ⁷⁵ 42 operating the swinging lever 36 must remain stationary which for example may be effected in that the control shaft 43 rotating periodically in either direction is connected with the control disc 42 by means of a mono-tooth coupling 45 in such manner that the control disc 42 is only driven when the control shaft rotates in the one direction and remains stationary when the control shaft ⁸⁰ rotates in the opposite direction. The projections 40 and 41 are arranged on the control disc 42 in such manner that the control disc 42 comes to rest when the projection 40, but not the projection 41, has already engaged ⁸⁵ with the swinging lever 36. To ensure this intermediate position a spring operated pawl 44 is provided which engages in a corresponding recess or notch 46 on the cam disc 42. ⁹⁰

What we claim is:—

1. A screw cutting device for automatic lathes comprising a tool mounted for rotative and axial movements, a unidirectionally rotated mandrel for effecting the forward and backward motion of said tool, a mandrel guide rotating in the same direction as the mandrel and threadedly engaged therewith, and mechanism for driving said mandrel alternately at higher and lower speeds than the speed of rotation of said guide, substantially as set forth. ¹⁰⁵

2. In an automatic lathe adapted for screw cutting, in combination, a mandrel, a mandrel guide driven at constant speed in threaded engagement with the mandrel, two gear trains adapted to drive said mandrel at different speeds, and a coupling member axially displaceable for engaging said mandrel with either of said gear trains, substantially as set forth. ¹¹⁰

3. In an automatic lathe for cutting screws, in combination, a blank rotating unidirectionally at constant speed, a tool mounted for rotative and axial movements, a mandrel for reciprocating said tool, a rotary guide driven at constant speed in threaded engagement with the mandrel, and means for rotating said mandrel alternately faster and ¹¹⁵ slower than the speed of rotation of the blank, substantially as set forth. ¹²⁰

slower relatively to the speed of said guide, substantially as set forth.

4. In an automatic lathe for cutting screws, in combination, a tool mounted for rotative and axial movements, a rotating mandrel for reciprocating said tool, a rotating guide for and engaging with said mandrel, two gear trains for driving said mandrel, a sliding sleeve for coupling either of said gear trains with said mandrel, and cam-operated spring-opposed lever mechanism for displacing said sleeve, substantially as set forth.

5. In an automatic lathe for cutting screws, in combination, a tool mounted for rotative and axial movements, a rotating mandrel for reciprocating said tool, a rotating guide for and engaging with said mandrel two gear trains for driving said mandrel, a sliding sleeve operatively engaging either of said gear trains with said mandrel, means for displacing said sleeve and means for locking said sleeve in its position, substantially as set forth.

6. In an automatic screw cutting lathe, in combination, a unidirectionally rotated mandrel guide, a unidirectionally rotated mandrel threadedly engaging with said guide, two gear trains for driving said mandrel at different speeds, coupling mechanism for engaging said mandrel with either of said gear trains, and means comprising a cam disc driven from the lathe for operating said coupling mechanism, substantially as set forth.

7. In an automatic screw cutting lathe, a mandrel guide rotated in one direction and a mandrel rotated in the same direction and threadedly engaged with said guide, substantially as and for the purpose set forth.

8. Automatic screw cutting machine, comprising in combination, a mandrel guide rotated at constant speed and a mandrel rotated in the same direction and connected with said guide for rotative and axial movement relative thereto, and mechanism for imparting motion to said mandrel substantially as described and illustrated in the accompanying drawings.

In testimony whereof we have signed our names to this specification.

50 OTTO SCHAEFER.
FRITZ POPPENSIEKER.
